CLAIM

The ornamental design for a package, as shown and described.

DESCRIPTION

1. Package for foodstuff
2. Package for foodstuff in collapsed form
- 1.1 : Perspective view
- 1.2 : First side view
- 1.3 : Front view
- 1.4 : Second side view
- 1.5 : Rear view
- 1.6 : Top view
- 1.7 : Bottom view
- 2.1 : Perspective view
- 2.2 : Front view
- 2.3 : First side view
- 2.4 : Rear view
- 2.5 : Second side view
- 2.6 : Top view
- 2.7 : Bottom view

The broken lines in the drawings illustrate portions of the package that form no part of the claimed design. The areas bounded solely by broken lines form no part of the claimed design.

The package for foodstuff illustrated in reproductions 2.1-2.7 corresponds directly to the package for foodstuff illustrated in reproductions 1.1-1.7. The packaging sheet for foodstuff illustrates the package for foodstuff in collapsed form.

1 Claim, 14 Drawing Sheets
